The ornamental design for a skin care massage tool, as shown and described.

DESCRIPTION

FIG. 1 is a perspective view of the skin care massage tool of the present invention;

FIG. 2 is a front elevation view of the skin care massage tool shown in FIG. 1;

FIG. 3 is a rear elevation view of the skin care massage tool shown in FIG. 1;

FIG. 4 is a left side elevation view of the skin care massage tool shown in FIG. 1;

FIG. 5 is a right side elevation view of the skin care massage tool shown in FIG. 1;

FIG. 6 is a top plan view of the skin care massage tool shown in FIG. 1; and,

FIG. 7 is a bottom plan view of the skin care massage tool shown in FIG. 1.

*The broken lines define an area of the skin care massage tool that is not considered part of the claimed design.***1 Claim, 7 Drawing Sheets****Matter enclosed in heavy brackets [ ] appears in the original patent but forms no part of this reissue; matter printed in italics indicates the additions made by reissue.****Fig. 1**
